CLAIM

The ornamental design for a container for food storage, as shown and described.

DESCRIPTION

FIG. 1 is a top perspective view of a container for food storage;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the figures are for the purpose of illustrating portions of the container for food storage and form no part of the claimed design.

1 Claim, 4 Drawing Sheets(56)
